UNITED STATES PATENT OFFICE.

WILLIAM HARRISON GREEN, OF HERNDON, WEST VIRGINIA.

DATE-HOLDER.

1,101,535.

Specification of Letters Patent. Patented June 30, 1914.

Application filed November 13, 1913. Serial No. 800,812.

To all whom it may concern:

Be it known that I, WILLIAM H. GREEN, a citizen of the United States, residing at Herndon, in the county of Wyoming and State of West Virginia, have invented certain new and useful Improvements in Date-Holders; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in racks for holding and delivering type having in rotation the names of the month and the numbers of the days in order and so arranged that, by actuating a spring-pressed plunger, the type bearing the name of the month and the days in succession may be delivered for use in stamping letters, etc.

The invention comprises a simple and efficient device of this nature having various details of construction and combinations and arrangements of parts which will be herein-after fully described, shown in the accompanying drawings and then specifically defined in the appended claim.

I illustrate my invention in the accompanying drawings, in which:—

Figure 1 is a front elevation of my invention. Fig. 2 is an edge view. Fig. 3 is a cross sectional view, and Fig. 4 is a longitudinal sectional view on line 4—4 of Fig. 1.

Reference now being had to the details of the drawings by letter, A designates a casing which may be of any convenient size or shape and adapted to have a base B for attachment to a table or other object or, if preferred, the casing may be suspended by hanging the device upon a nail passed through an aperture in the back of the same. Said casing is provided with a series of longitudinal partitions C, dividing the same into compartments and the front wall of the casing is cut away as at D to allow type to be delivered from the bottom of one or another of the series of type in the various compartments. Fastened to the rear of the

casing are the springs E having angled ends movable through the slots F formed one in the rear wall of each compartment adjacent to its lower end and in alignment with the cut-away portion at the bottom of the casing. The angled ends of said spring are adapted to act as plungers for pushing out the lowermost of the type in the bottom of the compartment.

In operation, it is my purpose to arrange in the various compartments at the bottom of each a type bearing the name of the months in succession, there being preferably one for each month of the year, and resting upon the lowermost of each type in each compartment a series of numerals designating in regular order the days of the month. When it is desired to utilize the type for placing the same in a socket or stamp, the operator may push upon the particular spring to cause type bearing the name of the particular month desired to be used and, when the lowermost type has been expressed or pushed from the compartment through the opening, the spring may be again pressed for as many successive type as may be desired. After the type have been used, they may be placed back in the top of the compartment.

In the drawings I have shown eight compartments within the casing and each one is adapted to have a type bearing the name or contraction of a distinct month or type having numerals, one for each day of the month.

By the provision of a device of this nature, it will be noted that a simple and efficient mechanism is afforded whereby the names of the months and days may always be kept in rotation.

What I claim to be new is:—

A date holder and delivering apparatus comprising a casing divided by series of parallel and vertically disposed partitions into a series of compartments, said casing having a front wall with slots registering one with each compartment and terminating at its upper end below the upper ends of said partitions, openings between the lower end of the front wall and the bottom of the casing, the upper ends of the latter being inclined, the lower part of the casing having a base extending in opposite directions beyond

the front and rear walls thereof, a series of springs fastened at their upper ends to the rear walls of the casing and the lower end of each spring being angled and in alignment with and adapted to be guided in a slot formed in the rear wall of the casing adjacent to said base.

In testimony whereof I hereunto affix my signature in presence of two witnesses.

WILLIAM HARRISON GREEN.
